CLAIM

The ornamental design for a puzzle table as shown and described.

DESCRIPTION

FIG. 1 is a perspective view of a puzzle table showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the puzzle table where drawers thereof are in a use position; and,

FIG. 10 is a perspective view of the puzzle table where the puzzle table is in a folded state.

The unshaded areas between solid and broken lines form no part of the claimed design.
